[57] CLAIM

The ornamental design for a refrigerator door compartment, as shown and described.

DESCRIPTION

FIG. 1 is front perspective view of a refrigerator door compartment showing my new design. The broken line showings of the frame of the refrigerator door are for illustrative purposes only and form no part of the claimed design;

FIG. 2 is a front elevational view showing my new design; FIG. 3 is a left side elevational view thereof, the right side being identical;

FIG. 4 is an enlarged top plan view thereof; and,

FIG. 5 is a bottom plan view thereof.
